UNITED STATES PATENT OFFICE

HARRY J. HERFF, OF INDIANAPOLIS, INDIANA, ASSIGNOR TO HERFF-JONES COMPANY, OF INDIANAPOLIS, INDIANA, A CORPORATION

DESIGN FOR A DECORATIVE PANEL FOR INSERTION IN JEWELRY

Application filed December 18, 1930. Serial No. 38,023. Term of patent 14 years.

To all whom it may concern:

Be it known that I, HARRY J. HERFF, a citizen of the United States, residing at Indianapolis, in the county of Marion and State of Indiana, have invented a new, original, and ornamental Design for a Decorative Panel for Insertion in Jewelry, of which the following is a specification, reference being had to the accompanying drawing, forming part thereof.

The figure is a plan view of the decorative panel for insertion in jewelry showing my new design, said panel being of inconsequential thickness.

I claim:

The ornamental design for a decorative panel for insertion in jewelry as shown and described.

HARRY J. HERFF.
